UNITED STATES PATENT OFFICE.

WALTER S. PAYNE, OF LINCOLN, NEBRASKA.

POWER-OPERATED HAMMER.

1,228,962.

Specification of Letters Patent. Patented June 5, 1917.

Application filed April 17, 1916. Serial No. 91,773.

To all whom it may concern:

Be it known that I, WALTER S. PAYNE, a citizen of the United States, residing at Lincoln, in the county of Lancaster and State of Nebraska, have invented certain new and useful Improvements in Power-Operated Hammers, of which the following is a specification, reference being had to the accompanying drawings.

10 This invention relates to certain new and useful improvements in power-operated hammers and has for its primary object to improve the construction and increase the utility of a power-operated hammer 15 of the type disclosed in Patent Number 1,158,270, issued to me October 26, 1915.

It is one of the principal objects of the present invention to provide simple and positively operating means for actuating 20 the hammer, said operating means including a cam capable of easy and quick removal whereby the same may be readily replaced by another cam and the extent of the power stroke of the hammer plunger 25 varied as may be desired by the operator.

It is another object of my invention to provide an improved mounting for the hammer plunger, whereby friction is reduced to a minimum, means being provided 30 to prevent the hammer becoming air-bound and thus obviate retardation of its retractile movement.

It is also one of the secondary objects of the invention to provide an improved 35 sectional construction of the casing for the operating parts and for the hammer plunger, whereby access may be readily had thereto for the purpose of replacing or repairing the mechanism.

40 It is still another object of my invention to provide in combination with the hammer, an oscillatable sleeve adapted to carry a chisel point, and means operatively connecting the sleeve to the shaft of the motor, 45 whereby the hammer is operated.

And finally, the invention has for its object to produce a power-operated hammer which will be light in weight and can be readily manipulated, strong and durable in 50 construction, and highly reliable and efficient in practical operation.

With the above and other objects in view, my invention consists in the novel features of construction, combination and arrangement of parts to be hereinafter more fully

described, claimed and illustrated in the accompanying drawing, in which,

Figure 1 is a side elevation, partly in section, showing the hammer plunger in its retracted position;

Fig. 2 is a transverse section taken on the line 2—2 of Fig. 1;

Fig. 3 is a section taken on the line 3—3 of Fig. 1;

Fig. 4 is a fragmentary perspective view 65 of the plunger head of the hammer;

Fig. 5 is a section taken on the line 5—5 of Fig. 1;

Fig. 6 is a front end elevation, the oscillatable sleeve being shown in section;

Fig. 7 is a detail elevation of the cam; and

Fig. 8 is a detail perspective view of one of the casing sections.

Referring in detail to the drawing, 5 designates the case for the hammer operating mechanism, with which the handle 6 is integrally formed. On its upper side, the case 5 is of semi-cylindrical form and, upon the same, a case section 7 of semi-circular 80 form in cross-section is adapted to be arranged. 8 designates two relatively long semi-cylindrical case sections which are substantially the counterpart of each other. The main casing 5 and the casing sections 85 7 and 8 are formed with laterally projecting lugs 9 to receive suitable fastening screws indicated at 10, whereby the several casing sections may be detachably connected together. 11 designates the motor case, the 90 body of which may be integrally formed with one of the hammer case sections 8, and to one end of this body a head section 12 is secured by means of the screws indicated at 13, and to said head section the case 5 95 for the operating mechanism is secured by the screws 14. This head plate is formed with an extension 15 interposed between the opposed ends of the case sections 7 and 8 for the hammer plunger. The other end 100 of the body 11 of the motor case is closed by a hollow head 16 through which the motor shaft 17 extends. In this hollow head 16 of the case, the motor armature is arranged. The several elements of the casings or housings for the motor, the hammer plunger, and the operating mechanism for the latter, are preferably formed of aluminum. The casing section 7 and the sections 105 8 for the hammer plunger are provided 110

with interior lining walls 18 of relatively thin steel. The steel lining of the casing sections 8 consists of two parts or sections, the opposed ends of which are threaded for a purpose to be hereinafter explained:

5 The motor shaft 17 is mounted in a suitable anti-friction bearing 19 arranged in the head plate 12 of the motor case. A steel plate 20 is arranged in the recessed face 10 of the head section 12 of the case over the bearing 19 and is suitably secured to the casing plate. This plate 20 is formed with an annular raceway 21 adjacent to its outer edge, and an internal gear 22 rotates contiguous to said plate within the case 5 and is also provided with a raceway in mating relation to the raceway 21. These raceways receive the anti-friction bearing balls 23.

Upon the end of the motor shaft 17 extending through an opening in the plate 20, 20 a pinion 24 is fixed and meshes with the internal gear 22. The other face of this gear is rabbeted at its outer edge so as to receive a flange formed upon the plate 25 which is 25 suitably fixed to said gear, or if desired, said plate may be integral with the internal gear.

26 designates the cam shaft which extends through a central hub formed on the 30 plate 25 and is mounted at its ends in suitable bearings 27. Upon the face of the plate 25, a metal ring 28 is fixed, and to said ring one end of a cam 29 is secured by means of screws indicated at 30. The maximum diameter of this cam is approximately 35 equal to the internal diameter of the case 5 and projects into the longitudinally extending, semi-circular extension formed upon the case wall within which the hammer 40 plunger to be later referred to, is movably disposed. The cam 29 is in the form of a cylindric plate, and the spiral cam edge of this plate, indicated at 31, extends substantially through the entire length of the casting 5, said cam edge extending from one side of the shaft 26 at the outer end thereof and terminating at its other end at a diametrically opposite point at the inner end of said shaft. At one end of the cam plate, 50 the same is provided with an obliquely inclined longitudinal edge 32 which extends from one end of the cam face 31 to the other end thereof.

The sections of the tubular metal lining 55 18 are connected by a coupling 33 which is exteriorly threaded for engagement with the interior threads on the opposed ends of said tube sections. In the bore of this coupling, the plunger rod 34 is slidably engaged. The hammer plunger 35 has threaded connection to one end of the plunger rod 34, and the inner end of this hammer plunger and the opposed end of the coupling 33 are recessed to receive the ends of a coil 60 spring 36 surrounding the plunger rod.

The other end of the plunger rod is slightly enlarged and formed with a flat bottom face in opposed relation to the surface of the cam plate 29. A pin or stud 37 is fixed in this end of the plunger rod, and in one side 70 thereof a roller 38 is suitably mounted for engagement upon the cam edge 31. Above this enlarged end of the plunger rod, anti-friction rollers 39 are suitably mounted in the semi-circular metal lining 18 of the casting section 7. These rollers serve as guides to permit of a free sliding movement of the plunger rod with a minimum of friction.

The hammer plunger 35 is provided with a plurality of longitudinally extending 80 ducts 35' which open upon the opposite end of the plunger and permit of the free passage of air from opposite sides of the plunger in its movement in each direction. The tubular shell or lining 18 within the casing 85 sections 8, projects for some distance beyond the end of the casing, as clearly shown in Fig. 1 and upon the same an oscillatable sleeve 40 is loosely engaged. Upon the end of the motor shaft 90 17, projecting through the casing head 16, a disk 41 is fixed, and to the same one end of a pitman rod 42 is connected, the other end of said rod being pivotally connected to one side of the sleeve 40, as shown 95 at 43. This sleeve is equipped with a suitable cutting edge and is of material advantage in certain operations, such as trimming the heads of rivets as they are swaged or hammered down.

100 In the operation of the device, the motor being set in operation, rotation is transmitted to the internal gear 22 and to the cam 29 mounted upon said gear. As shown in Fig. 1 of the drawing, as this cam rotates the edge 31 thereof acting against the roller 38 on the pin or stud 37, moves or draws the hammer plunger inwardly against the action of the spring 36 and places said spring under tension. The roller 38 finally moves off the higher end of the cam 29 and the spring 36 then immediately acts to force the hammer plunger 35 outwardly and deliver a powerful blow upon the rivet or other object over which the hammer is set. The roller 38 travels along the inclined edge 32 of the cam plate to the lower side of its spiral edge 31, and in the continued rotation of the cam the roller will again move along this cam edge to the higher side 110 of the cam and the plunger will be retracted into position to deliver another blow when the plunger rod is again released.

115 From the foregoing description, taken in connection with the accompanying drawing, the construction, manner of operation and several advantages of the invention will be clearly and fully understood. By 120 the sectional construction of the case for the various parts of the device, access may 125 130

be readily had thereto for the purpose of repairing the same, and the cam 29 can also be easily and quickly removed and replaced by another cam of different form, whereby the extent of movement of the hammer plunger may be varied and its operating movements quickened or accelerated, as desired. By the provision of the air ducts or ports 35' in the hammer plunger, the plunger will not be air-bound or cushioned and its action thereby retarded. Undue strain upon the operating parts of the mechanism is thus avoided. By the provision of the rollers 39, frictional contact of the hammer plunger with the walls of the casing is prevented and the rod and plunger also held against rotative movement within the casing. The device as a whole is very simple and durable in its construction, highly reliable and positive in operation, and may be manufactured at relatively small cost.

While I have shown and described the preferred construction and arrangement of the several elements, it is to be understood that the invention is susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:—

1. In a power-operated hammer, a reciprocating plunger, a spring urging said plunger in one direction, a rotatable cam having its axis of rotation disposed in spaced parallel relation to the longitudinal axis of said plunger, means for rotating said cam, and means connected to the plunger operatively engaged with the cam, said cam being constructed to move the plunger in one direction against the action of said spring and then suddenly release the plunger whereby its movement is reversed under the expansive action of the spring.

2. In a power-operated hammer, a hammer plunger, a rod connected thereto, a power shaft, a rotatably mounted disk geared to the power shaft, a cam plate detachably secured at one end to the periphery of said disk, a spring surrounding said rod and urging the hammer in one direction, and means on said rod co-operatively engaged with the cam, said cam being constructed to retract the plunger rod and hammer against the action of said spring and then suddenly release the plunger rod whereupon the power stroke of the hammer is delivered under the expansion action of the spring.

3. In a power-operated hammer, a hammer case, a hammer to reciprocate therein, a rod connected to the hammer, a spring surrounding said rod and urging the hammer

in one direction, anti-friction rollers engaging one end of the rod and preventing a turning movement of the same, a rotatable cam, means for operating said cam, and a roller mounted upon one end of the rod and co-operatively engaged with the cam, said cam being constructed to move the roller in one direction against the action of said spring and then suddenly release the plunger, whereupon the power stroke of the hammer is delivered under the expansion of the spring.

4. In a power-operated hammer, a case, a plunger hammer to reciprocate in said case, a rod connected to the plunger hammer, a guide for the rod, a spring arranged between the guide and the hammer to move the hammer in one direction, means mounted in the case and engaged by the rod to prevent rotative movement of the latter, a rotatably mounted internal gear, a power shaft operatively engaged with said gear, a disk carried by the gear, a cam removably mounted upon said disk, and means on one end of the rod co-operatively engaged with said cam, whereby the rod is moved in one direction in the rotation of the cam and said spring placed under tension, said cam being so constructed as to suddenly release the rod and permit of the expansive action of the spring to deliver the power stroke of the hammer.

5. In a power-operated hammer, a casing, a plunger hammer mounted to reciprocate in said casing, a rod connected to the hammer, a guide in the casing for said rod, a spring arranged between said guide and the hammer and urging said hammer in one direction, said hammer being provided with a plurality of longitudinally extending air ducts, and operating means for the hammer including a rotatable cam and means on one end of said rod operatively engaged with the cam, said cam being constructed to move the rod and hammer in one direction against the action of said spring and then suddenly release the same to permit of the expansion of the spring and the delivery of the power blow of the hammer.

6. In a power-operated hammer, a motor case, a case for the hammer operating mechanism detachably mounted upon one end of the motor case and having a handhold integral therewith, a plunger hammer and rod, and a sectional casing therefor detachably secured upon said first named casings.

7. In a power-operated hammer, a casing, a reciprocating hammer plunger, operating means therefor, a motor to actuate said operating means, a sleeve loosely mounted to oscillate upon one end of said casing and having cutting teeth on one end, and means operatively connecting one end of the motor shaft to said sleeve to oscillate the same in the operation of the hammer.

4
8. In a power-operated hammer, a casing, a reciprocating hammer plunger, operating means therefor, a motor to actuate said operating means, a sleeve loosely mounted to oscillate upon said end of said casing and having cutting teeth on one end, a crank arm fixed to one end of the motor shaft, and a pitman rod connection between the crank arm and one side of said sleeve to oscillate the latter in the operation of the hammer.

10 9. In a power operated hammer, a reciprocating plunger, a spring urging said plunger in one direction, a rotatable cam having its axis of rotation disposed in spaced parallel 15 relation to the longitudinal axis of the plunger, said cam having a helical end face, means on the plunger coacting with said cam face, said plunger being retracted in the rotation of the cam and suddenly released by 20 the disengagement of the helical cam from the means on the plunger thereby permitting the expansive action of the spring to deliver the power stroke of the hammer.

25 10. In a power operated hammer, a hammer case, a hammer to reciprocate therein,

a fixed guide mounted in the casing, a rod connected to the hammer movable through said guide, a spring disposed between said guide and the hammer and urging the hammer in one direction, a rotary cam mounted at one side of said rod, and means on the rod coacting with the cam whereby the hammer is actuated in the rotation of the cam.

30 11. In a power operated hammer, a hammer case, a hammer to reciprocate in said case, a rod connected to the hammer, a spring mounted in the case and urging the hammer in one direction, and rotatable means arranged at one side of said rod and having its rotative axis disposed in parallel 35 relation to the longitudinal axis of the rod, said rod being provided with means coacting with said rotatable means whereby the hammer is actuated.

40 In testimony whereof I hereunto affix my 45 signature in the presence of two witnesses.

WALTER S. PAYNE.
